UNITED STATES PATENT OFFICE

ARMISTEAD R. LONG, OF SCARBRO, WEST VIRGINIA

CAR STOP

Application filed December 19, 1929. Serial No. 415,312.

This invention relates to improvements in car stops particularly well adapted for the prevention of rolling stock from traveling down-hill upon a trackway.

The primary object of the invention is the provision of an improved type of car stop which is particularly well adapted to be used in connection with mine cars, to limit movement thereof down-hill; the same comprising a portion which may be slipped endwise onto the rail in such manner that it cannot be laterally displaced therefrom, thus insuring a positive connection upon the rail; the same being so formed as to grip either the base or the head of the rail, depending upon the position of the rail, for the purpose of anchoring thereto and preventing end movement of the car upon the rail.

A further object of the invention is the provision of an improved type of car stop, which in many general features was originally disclosed in my application, Serial No. 358,641, filed April 27, 1929, consisting of an upright portion adapted to be extended above the rail, and including a socket portion which may be assembled upon the rail so as to grip the same with a biting action to prevent longitudinal sliding along the rail.

A further object of the invention is the provision of an improved type of car stop including means to attach the same to a rail against longitudinal movement, and having an improved type of sprag flexibly connected thereto for cooperatively locking a car chassis against down-hill movement upon the trackway.

A further object of this invention is the provision of an improved type of car stop which may be operatively associated upon a trackway when in a normal or upright position, or when in an inverted position as set forth in my application above referred to, for the purpose of preventing down-hill movement of cars over the rails of the trackway.

Other objects and advantages of this invention will be apparent during the course of the following detailed description.

In the accompanying drawings, forming a part of this specification, and wherein simi-

lar reference characters designate corresponding parts throughout the several views,

Figure 1 is a perspective view of the improved car stop.

Figure 2 shows the improved car stop with the sprag portion thereof gripping the wheel and frame to prevent down-hill movement of a mine car.

Figure 3 is a perspective view showing the car stop with the rail attached portion thereof preventing down-hill movement of the mine car in opposite direction from that shown in Figure 2.

Figure 4 is a side elevation showing the attachment of the improved car stop to an inverted rail such as are sometimes used for trackway extension purposes in the laying of mine trackway; the car stop being shown connected to the inverted rail without any positive bolting, so that it will yet perform its car stop operation.

Figure 5 is a transverse sectional view through the inverted rail of Figure 4, showing the relation in which the car stop grips the same.

Figure 6 is a view showing the pivotal connection of the car stop upon an inverted rail, and with the chain extended as would be the case when the sprag is used for preventing down-hill movement of a car.

Figure 7 is a side elevation showing attachment of the car stop as by a pivot bolt to a trackway when in a normal or upright position.

Figure 8 is a view of the car stop attached to an upright rail, against which a wheel is acting to prevent movement of a mine car down hill along a rail.

Figure 9 is a sectional view taken through an upright rail showing the car stop in relation shown in Figure 8.

In the drawings, wherein for the purpose of illustration is shown only a preferred embodiment of the invention, the letter A may generally designate the improved car stop, which comprises a rail gripping stop portion B having a sprag C attached thereto as by a chain or other flexible means D.

The car stop portion B is formed of a piece of band or bar metal of rectangular cross sec-

tion, which is bent intermediate the ends thereof, at 10, and doubled in engagement with itself at 11 and 12^a to provide a vertical or upright shank 12; the portions 11 and 12^a being welded together throughout their facing surfaces for the purpose of reinforcing and strengthening the shank. The ends of the bar from which the improved stop portion B is formed are shaped to provide sockets for engaging either the normal base or head of the rail, depending upon its upright or inverted positioning, in order to anchor the portion B. The specific manner of forming the sockets of the rail clamp B is shown in the drawings, and consists in bending the ends at the base of the shank, to provide shoulders 13 and 14 at right angles to the axis or plane of the shank 12. At the outer ends of the shoulders 13 and 14, the ends of the material out of which the portion B is formed are bent at right angles downwardly at 15 and 16 respectively, and then flanged inwardly in right angled relation at 17 and 18 respectively, in spaced parallelism below the shoulders 13 and 14 respectively; the flanges 17 and 18 terminating in spaced relation at their facing ends. The free end portions or flanges 19 and 20 are formed in substantial parallelism with respect to each other, and in spaced parallel relation with their respective adjacent portions 15 and 16. The top edges of the flanges 19 and 20 are spaced from the downwardly facing surfaces of the shoulder portions 13 and 14, and these spaces provide the sockets for receiving base flanges or head flanges of the rail at opposite sides of the plane of the web of the rail, as is illustrated in various views of the drawings.

The spaced portions 15, 19, 20 and 16 of the drawings are each provided with a transverse opening 22 therein; all of said openings 22 aligning for the purpose of receiving a pivot bolt 24, more particularly shown in Figure 9 of the drawings, which is used in attaching the portion B to the rail under certain circumstances to be subsequently mentioned. As best shown in Figure 5 of the drawings the upper edges of the spaced flanges 19 and 20 are beveled at 26 in a downwardly convergent relation towards the web receiving space 30 between said flanges; the said edges 26 being adapted to grip the sloping or inclined surfaces at the under sides of the rail head flanges, or at the under sides of the normal base flanges of the rail when inverted as shown in Figure 5. The upper corners of the shank 12 are preferably removed to bevel the shank at 27, for better receiving the car wheel thereagainst, as shown in Figures 4 and 8 of the drawings.

The shank 12 near its upper end is provided with a transverse opening 30, through which a large attaching link 31 of the flexible connection D is loosely positioned. The flexible

connection D is preferably a metal chain consisting of connected links 34, sufficiently strong to withstand the shock of car stoppage thereupon. The link 31 is so connected in the opening 30 as to permit its swinging in the plane of the shank 12, from the front to the rear of the rail engaging stop portion B over the top of the shank 12.

The sprag C is preferably a metal bar having a solid cross section. It is preferably cylindrical and intermediate its ends it is provided with an enlargement at 35 having a transverse opening 36 through which an end link 37 of the chain D is loosely pivoted. The sprag C is preferably straight from end to end, and provides a handle portion 40^a at one end and a longer detent portion 42^a at the other side of the pivot link 37, which is adapted to be inserted between the spokes of the wheel of a car chassis to engage the frame or some portion of the car chassis to lock the wheel against complete rotary movement. It is made sufficiently long for that purpose. The free end of the portion 42 is tapered at 44 to facilitate its insertion between the spokes of the wheel.

It is to be particularly noted that the lower end edges of the flanges 13 and 14 and the upper facing end edges of the flanges 19 and 20 are sharp and well defined, being chisel-like in nature, for the purpose of biting into the upper and under surfaces of both the head and base flanges of the rail, depending upon the position in which the car stop is used.

Referring to the application of the improved car stop upon an inverted extension rail, as shown in Figures 4 and 5 of the drawings, it is readily apparent that due to the restricted space between the facing surfaces of the flanges 19 and 20, the car stop proper B must be slipped endwise onto the rail, and the base flanges 40 and 41 of the rail are received in the socket above the top edges of the flanges 19 and 20, and below the upper flanges 13 and 14 of the car stop member B, with the web 42 of the inverted rail in the space between the flanges 19 and 20. The head of the inverted rail of course rests upon any suitable roadbed provided therefor. In this position it is to be noted that the car stop member B is rockable through a slight arc in its supported position upon the base flanges of the rail. Assuming that there is a tendency of the car to roll down-hill upon the rail G, in the direction of the car stop portion B, the latter will receive the traveling force of the wheel and truck thereagainst. It will tip the member B and the corner edges of the flanges 19 and 20 will bite into the under surfaces of the rail base flanges 40 and 41, as inverted, at the point designated at 50 in Figure 4 of the drawings, and at the down-hill side of the car stop member B, which has been tipped to the position shown in Figure 4, the end edges of the flanges 13 and 40

- and 14 will bite into the top surfaces of the base flanges 40 and 41, as designated at the point 51 in Figure 4. This effectively prevents the car stop member B from sliding 5 along the inverted rail, and will hold the car in position against farther down-hill movement. This may be effectively accomplished without the necessity of bolting the car stop member B to the inverted rail. It has been 10 found that under such circumstances there is no liability of slipping of the member B along the rail due to contact of car wheels thereagainst, as an incident of even a greater than ordinary shock contact of the car wheels. 15 The use of the entire device under such circumstances is also illustrated in Figure 3 of the drawings. Assuming that the car is at the down-hill side of the member B as assembled upon the inverted rail, as shown in 20 Figure 2 of the drawings, the sprag C is inserted between the spokes of the wheel 54 of the mine car, as shown in Figure 2 of the drawings, which will of course effectively prevent complete rotation of the wheel, since 25 the sprag will catch against some other part of the chassis of the car. With such use of the invention, assuming the rail to be inverted in the position shown in Figures 2 and 6 of the drawings, the member B may be 30 pivotally secured by the bolt 24, to the web of the inverted rail, as by slipping the bolt 24 through one of the fish plate bolt openings of the rail. The travel of the mine car down-hill with the sprag between the wheels will 35 cause a tipping of the member B upon the bolt 24 as a pivot axis, and prior to any shearing effect upon the bolt, the sharp end edges of the flanges 19 and 20 and shoulders 13 and 14 will come into engagement with 40 the top and under surface of the base flanges of the inverted rail G, at the points 56 and 57 indicated in Figure 6 of the drawings.
- In using the improved device upon rails in their normal upright position, as shown in 45 Figures 7, 8 and 9 of the drawings, it is preferred under all circumstances to pivotally bolt the member B to the web of the rail as above described. Under these circumstances, where the car stop member B is at the down-side of the rolling truck, as shown in Figure 8, the socket facing sharp edges of the flanges 13, 14, 19 and 20 will bite into engagement 50 with the top and under surfaces of the flanges of the head 60 of the rail, at opposite sides of the plane of the web of the rail, as at the points 61 and 62 indicated in Figure 8 of the drawings. In using the sprag of the device A, under circumstances where the car is at the down-side of the member B assembled 55 upon the rail, the member B will move through a slight arc to the position shown in Figure 7 and the end edges, facing the sockets, upon the flanges 13, 14, 19, and 20 will bite into the upper and lower surfaces of the 60 flanges of the ball or head of the rail at the points indicated at 65 and 66 in Figure 7 of the drawings.
- It is within the contemplation of this invention not to bolt or pivot the member B in a positive relation upon the rail, since the rail flange engaging edges of the member B may be suitably formed to bite into the surfaces of the flanges of the rail, whether upright or inverted, to prevent sliding along the rail, and to anchor the car against movement. However, when the bolt 24 is used, as above mentioned, the edges of the flanges of the member B bite into the upper and lower surfaces of the head or base flange of the rail, depending upon its position, at a time prior to the 70 shearing shock coming upon the bolt. It is also within the contemplation of the invention to provide a device which will not rock longitudinally upon the rail when assembled thereupon, and employ it in connection with a sprag and flexible connecting chain or cable. In considering the structure of the member B it must be borne in mind that its vertical height above the top of the rail, whether inverted or upright, is limited, since 80 the frames of mine cars are very low slung. It has been found necessary to limit the height to four and one-half inches above the top of the rail.
- Various changes in the shape, size, and arrangement of parts may be made to the form of invention herein shown and described, without departing from the spirit of the invention or the scope of the claims.
- I claim:
1. In a car stop the combination of a rail, a car stop attached to the rail including a stop shank extending upwardly from the rail for car stopping purposes, a sprag for engagement with the car wheel, and a flexible connection between the sprag and car stop.
  2. In a car stop mechanism the combination of an inverted rail having an upturned normal base portion, a car stop including a stop shank provided with a depending socket portion attachable from an end of the rail only in an anchoring raised relation upon the normal base of the rail with the stop shank extending upwardly from said normal base of the inverted rail, said socket portion including depending parts at each side of the web of the inverted rail extending beneath the base flanges of the inverted rail, the socket portion having aligning openings transverse therethrough and the rail web 100 having a transverse opening, and a detachable bolt extending through all of said openings for pivotally connecting the car stop upon the web of the rail in a manner to permit the car stop to bite into the upper and lower surfaces of the base flanges of the inverted rail without shearing the bolt as an incident of a car stopping operation.
  3. As an article of manufacture a car stop to be used upon the rails of trackways com- 130

prising a stop shank having at the lower end thereof oppositely extending transverse flanges, said flanges at the outer margins thereof having depending portions, said depending portions at the lower margins thereof having inwardly extending transverse flanges terminating in spaced relation, the facing margins of said last mentioned flanges having upturned relatively spaced flanges terminating at their upper margins spaced below the first mentioned flanges to define with said first mentioned flanges rail flange receiving sockets.

4. As an article of manufacture a car stop to be used upon the rails of trackways comprising a stop shank having at the lower end thereof oppositely extending transverse flanges, said flanges at the outer margins thereof having depending portions, said depending portions at the lower margins thereof having inwardly extending transverse flanges terminating in spaced relation, the facing margins of said last mentioned flanges having upturned relatively spaced flanges terminating at their upper margins spaced below the first mentioned flanges to define with said first mentioned flanges rail flange receiving sockets, the first mentioned flanges and the last mentioned flanges having at the ends thereof sharp rail flange biting edges facing said sockets.

5. As an article of manufacture a car stop to be used upon the rails of trackways comprising a stop shank having at the lower end thereof oppositely extending transverse flanges, said flanges at the outer margins thereof having depending portions, said depending portions at the lower margins thereof having inwardly extending transverse flanges terminating in spaced relation, the facing margins of said last mentioned flanges having upturned relatively spaced flanges terminating at their upper margins spaced below the first mentioned flanges to define with said first mentioned flanges rail flange receiving sockets, the first mentioned flanges and the last mentioned flanges having at the ends thereof sharp rail flange biting edges facing said sockets, said last mentioned flanges at their upper edges being beveled in downwardly divergent relation with respect to the space between said last mentioned flanges.

6. As an article of manufacture a car stop to be used upon the rails of trackways comprising a stop shank having at the lower end thereof oppositely extending transverse flanges, said flanges at the outer margins thereof having depending portions, said depending portions at the lower margins thereof having inwardly extending transverse flanges terminating in spaced relation, the facing margins of said last mentioned flanges having upturned relatively spaced flanges terminating at their upper margins spaced

below the first mentioned flanges to define with said first mentioned flanges rail flange receiving sockets, said depending portions and last mentioned flanges having relatively aligning transverse bolt receiving openings therethrough.

7. As an article of manufacture a car stop to be used upon the rails of trackways comprising a stop shank having at the lower end thereof oppositely extending transverse flanges, said flanges at the outer margins thereof having depending portions, said depending portions at the lower margins thereof having inwardly extending transverse flanges terminating in spaced relation, the facing margins of said last mentioned flanges having upturned relatively spaced flanges terminating at their upper margins spaced below the first mentioned flanges to define with said first mentioned flanges rail flange receiving sockets, the first mentioned flanges and the last mentioned flanges having at the ends thereof sharp rail flange biting edges facing said sockets, said last mentioned flanges at their upper edges being beveled in a divergent relation with respect to the space between said last mentioned flanges, said depending portions and last mentioned flanges having relatively aligning transverse bolt receiving openings therethrough.

8. In a car stop device the combination of a stop shank, and means for connecting the stop shank to the flanges of a conventional rail for limited rocking movement in either direction longitudinally of the rail to a non-sliding gripping relation with said flanges.

9. In a car stop the combination of a stop shank, means to pivot the stop shank to a rail for limited rocking movement with the stop shank extending upwardly above the rail, and means for biting into the upper and lower surfaces of the laterally extending flanges at the top of the rail to limit the tipping movement of the stop shank at a time prior to the placement of a shearing force upon the pivot as a result of a car stopping operation.

10. In a car stop the combination of a stop shank, means attaching the stop shank to a rail in a car stopping relation with the rail, a sprag, and a flexible link chain connecting the sprag with the upper end portion of the shank of the car stop so that it may be swung to either side of the shank out of the way of the car wheel.

ARMISTEAD R. LONG. 120
